UNITED STATES PATENT OFFICE.

JOHN R. THOMAS, OF CINCINNATI, OHIO.

SAND-DRUM FOR SANDPAPERING-MACHINES.

SPECIFICATION forming part of Letters Patent No. 275,733, dated April 10, 1883.

Application filed January 27, 1883. (No model.)

To all whom it may concern:

Be it known that I, JOHN R. THOMAS, a citizen of the United States, and a resident of Cincinnati, in the county of Hamilton and State of Ohio, have invented certain new and useful Improvements in Sand-Drums for Sandpapering-Machines, of which the following is a specification.

My invention relates to improvements in sand or polishing drums, particularly that class used in sandpapering-machines.

The principal object of my invention is to provide the peripheral face of a sand-drum with one or more polishing-brushes.

Another object of my invention is to provide in the face of the drum or roller grooves or depressions, in which the sand-paper, its backing, and the frames of the brush or brushes set and are properly secured in place by bolts or otherwise.

In the accompanying drawings, Figure 1 is an end view of a sand-drum embodying my invention, showing three brushes on its peripheral face; and Fig. 2 is a longitudinal elevation of the same, showing one of the brushes secured in position.

A represents a cylinder or the drum proper, having the spider-arms or spokes B and hub C, for mounting it on its rotating shaft.

D D D represent longitudinal grooves or depressions made in the peripheral face of drum A.

E are bars or strips, usually of wood, fitting in the grooves D.

e are countersunk faces in the bars E.

F represents the sand-paper wound upon the drum A, with an intervening cushion or backing composed of a layer of rubber, f, and a layer of carpet, f'.

G G represent brushes arranged at suitable intervals apart on the peripheral face of the drum, their frames g resting in the depressions formed by pressing or forcing the sand-paper and its cushioned backing into the countersunk faces e of the bars E, to secure them in place on the drum, and having the bristles g' projecting slightly beyond the peripheral line of the sand-paper sufficient to come in suitable contact with the object to be polished.

Instead of the bristles g' of the brushes G, cloth, carpet, chamois, tampico, or other similar polishing material could be used; but

they would not be as good for general purposes. The brushes G are secured in place by screws or bolts H, passing through their frames g into and through the sand-paper, cushioning rubber and carpet, the backing-bars E, and the drum A, thereby securing all the said parts firmly upon the drum.

To provide for the wear of the bristles of the brushes G, bars of greater thickness could be introduced in the depressions D in place of the bars E; or additional strips could be introduced between the brushes and the drum A in any desirable manner.

It is obvious that but one brush could be used instead of three, as shown, where it would be desirable, or where occasion would require. It is also obvious that the brushes could be constructed and arranged spirally in corresponding grooves or depressions on the face of the drum; but such a construction would be expensive and inferior to that herein shown and described, which I consider the best for general purposes.

The operation of my sand-drum upon lumber results in a hard highly-polished surface, this being occasioned by the combination of the sand-paper and the polishing-brushes on the same drum and operating in unison.

I do not desire to confine myself to the precise construction of the drum and the arrangement of the sand-paper and its adjuncts upon it, as herein shown, as it is obvious various modified changes could be made in these parts without materially affecting the object of my invention herein described and claimed.

I claim—

1. A polishing-drum composed substantially of a cylinder surfaced with sand-paper, and provided with a longitudinal depression containing the frame of a brush which extends the entire length of the cylinder, with the bristles of the brush projecting slightly beyond the surface of the sand-paper, substantially as described.

2. A sand-drum for a sandpapering-machine, covered on its peripheral face with sand-paper or other polishing material, and having alternate series of polishing-brushes and sand-paper, arranged, combined, and adapted to operate substantially as herein set forth.

3. A sand-drum having its peripheral face covered with sand-paper or other polishing ma-

terial, combined with a series of brushes secured to the drum to form a surface of alternating brushes and sand-paper, substantially as described.

5 4. A polishing-drum for a sandpapering-machine, having a portion of its peripheral face covered with sand-paper or other similar polishing material, and alternating with one or more cleaning-brushes, forming a portion or

portions of its peripheral face, substantially as herein set forth.

In testimony whereof I have hereunto set my hand in the presence of two subscribing witnesses.

JOHN R. THOMAS.

Witnesses:

THOS. P. EGAN,
JNO. E. JONES.
